(57) CLAIM

The ornamental design for a seat, as shown and described.

DESCRIPTION

FIG. 1 is a front perspective view of a seat showing the new design;

FIG. 2 is a top view thereof;

FIG. 3 is a rear perspective view thereof;

FIG. 4 is a rear elevational view thereof;

FIG. 5 is a front elevational view thereof;

FIG. 6 is a side elevational view thereof, the opposite side elevational view being a mirror image;

FIG. 7 is a front perspective view of a second embodiment of the seat;

FIG. 8 is a top view thereof;

FIG. 9 is a rear perspective view thereof;

FIG. 10 is a rear elevational view thereof;

FIG. 11 is a front elevational view thereof;

FIG. 12 is a front perspective of a third embodiment of the seat;

FIG. 13 is a top view thereof;

FIG. 14 is a rear perspective view thereof;

FIG. 15 is a rear elevational view thereof; and,

FIG. 16 is a front elevational view thereof.

The broken lines shown are for environmental purposes only and form no part of the claimed design.
